UNITED STATES PATENT OFFICE.

JOHN J. PUNKE, OF DETROIT, MICHIGAN, ASSIGNOR TO HUPP MOTOR CAR CORPORATION, OF DETROIT, MICHIGAN, A CORPORATION OF VIRGINIA.

DESIGN FOR AN INSTRUMENT-PANEL FACEPLATE.

Application filed June 4, 1928. Serial No. 26,991. Term of patent 7 years.

To all whom it may concern:

Be it known that I, JOHN J. PUNKE, a citizen of the United States of America, residing at Detroit, in the county of Wayne and State of Michigan, have invented a certain new, original, and ornamental Design for Instrument-Panel Faceplates, of which the following is a specification, reference being had therein to the accompanying drawings, in which—

Fig. 1 is a front elevation of the instrument panel face plate showing my new design, and Figures 2, 3, 4, 5 and 6 respectively are enlarged sectional views taken on the lines 2—2, 3—3, 4—4, 5—5 and 6—6, respectively, of Fig. 1.

I claim:

The ornamental design for an instrument panel face plate, substantially as shown.

JOHN J. PUNKE.
